UNITED STATES PATENT OFFICE.

CURTIS P. CONARD, OF ISSAQAH, WASHINGTON.

PACKAGE HOLDER AND OPENER.

Application filed May 25, 1925. Serial No. 32,730.

The invention is a cover for cigarette packages having an opening in one corner through which the paper may readily be removed from a corner of the package.

5 The object of the invention is to provide a means for efficiently opening a package of cigarettes or the like.

Another object of the invention is to provide a cover for a package of cigarettes or 10 the like which will protect the package.

A further object of the invention is to provide a cover with openings at the corners through which a package that may be placed therein may be opened.

15 And a still further object of the invention is to provide a device into which a package may be placed which has means therein for cutting the package open.

With these ends in view, the invention embodies a thin metallic casing having one side open, an opening in the opposite side, an opening in one corner, a means for removing a package from the casing, a cover for the opening in the side of the casing 25 and another cover for the opening at the corner.

Other features and advantages of the invention will appear from the following description, taken in connection with the drawings, wherein:—

Figure 1 is a side elevation of the device showing it mounted upon a stand.

Figure 2 is a sectional plan showing the apparatus for moving a package out of the 35 casing.

Figure 3 is a front view of the casing showing a knife in the upper corner for cutting a package.

40 Figure 4 is a sectional plan showing the knife.

Figure 5 is a side view showing the casing in a simplified form without the covers or package removing means.

45 Figure 6 is a view showing a movable knife.

In the drawings I have shown my device as it would be made wherein numeral 1 indicates the casing, numeral 2, the opening 50 at the corner of the casing and numeral 3 the package removing means.

In the design shown, the casing 1 is made 55 of a rectangular shape with the end 4 curved as shown in Figure 2 and the end 5 substantially square. The end 5 may be opened or provided with a cover 6 having a snap 7 in the edge by which it may be held in

the closed position, and the end 4 may be provided with an opening 8 as shown in 60 Figure 3.

The inner edge 9 of the opening 2 should be placed back from the edge of the casing just far enough to permit the seal to be broken as the corner of the package of cigarettes is removed and the edge 10 should be down far enough to permit a cigarette to be taken from the package. The inner corner 11 should be rounded as shown in Figure 5 so that the cover of the package may be torn with a rounded corner to provide 65 a neat appearance. This opening 2 may be provided with a cover 12 which may be hinged to the casing at the point 13 and which may extend down over the edges of the opening so that the opening will be completely closed. The outer side of the cover 70 12 may be provided with an indentation 14 that may snap over a projection on the casing to hold the cover in the closed position. It will be observed that the cover 12 may be of any suitable design or may be omitted if desired as shown in Figure 5 and the opening 2 may be of any suitable shape 75 or size. Other openings as indicated at the points 15 and 16 may be provided in the casing so that the corners of packages may be cut off or the entire edge of the package may be removed by cutting across the openings.

At the inner side of the end 4 is a curved plate 17 having an arm 18 projecting along the inner side of the casing and the end of the arm 18 may be provided with a button 19 which extends through a slot 20 in the 80 casing. A spring 21 may be provided connecting the button 19 to the end of the casing so that it will be resiliently held in the position shown. It will be observed that after a package has been opened the cover 6 may be opened, if a cover is used, and the button 19 may be moved toward the open end 5 so that the package will be ejected therefrom. Package is pushed outward by putting the fingers in the opening 8 and pushing the package out of the rear. It will be observed that the side of the casing is bent outward to provide a groove for the spring 21 and the button 19.

The casing may have a knife as indicated 85 by the numeral 22 and shown in Figures 3 and 4 and 6 located along one edge so that a package may be cut as it is forced into the casing. It is understood that this knife

may be stationary or movable in an opening, or of any suitable design and may be located in any suitable manner. It will be observed that the knife is in the upper corner of the 5 casing and will cut the side of the package along the upper edge as the package is forced into the casing. A roughened surface 23 may be provided on the casing for scratching matches and the casing may be 10 provided with a stand as indicated by the numeral 24 when it is used on counters or in stores or the like.

It will be understood that changes may be made in the construction without departing 15 from the spirit of the invention. One of which changes may be in the design of the casing; another may be in the location or size of the opening or in the use of a different style of opening at each corner or in the 20 use of either of the openings with the design shown in Figure 1, and still another may be in the design of the ejector, as it is understood that any suitable means may be used for forcing the package out of the casing.

25 The construction will be readily understood from the foregoing description. To use the device, for cutting a package of cigarettes or the like, the package may be inserted into the open end 5 of the casing and 30 it will be observed that by tearing the cover of the package around the edge of opening, the package will have a neat opening through which the cigarettes may readily be taken and the seal of the package will 35 be broken. The package of cigarettes may then be readily removed from the casing or if desired, the cigarettes may be kept in the casing so that as the package is placed in the pocket it will not be broken or injured.

40 The movable knife shown in Figure 6 and

which may be held in a slot may be moved backward or forward, or around to cut any type of opening that may be placed in the device.

It is also understood that this device may 45 be used for all kinds of packages in addition to cigarette packages, such as breakfast foods and other package goods.

Having thus fully described the invention, what I claim as new and desire to secure by 50 Letters Patent, is:—

1. In a device of the class described, a rectangular shaped casing having an opening in one corner thereof, said opening being of sufficient size to permit the corner of 55 a package that may be placed therein to be torn away and the seal of the said package broken, said casing having another opening in one edge below the said former opening, a hinged closure at the opposite side of the 60 casing, a hinged cover for the opening in the corner of the said casing, and a suitable means for ejecting the package from the said casing.

2. In a device of the class described, a 65 rectangular shaped casing having an opening in one corner thereof, said opening being of sufficient size to permit the corner of a package that may be placed therein to be torn away and the seal of the said package 70 broken, a sharp edge extending into the said casing to engage and cut the said package, said casing having another opening in one edge below the said former opening, a hinged closure at the opposite side of the 75 casing, a hinged cover for the opening in the corner of the said casing, and a suitable means for ejecting the package from the said casing.

CURTIS P. CONARD.
